UNITED STATES PATENT OFFICE.

FRANK M. VOGAN, OF CANTON, OHIO.

DESIGN FOR SHEET METAL.

46,518.

Specification for Design.

Patented Oct. 6, 1914.

Application filed August 20, 1913. Serial No. 785,791. Term of patent 7 years.

To all whom it may concern:

Be it known that I, FRANK M. VOGAN, a citizen of the United States, residing at Canton, in the county of Stark and State of Ohio, have invented a new, original, and ornamental Design for Sheet Metal, of which the following is a specification, reference being had to the accompanying drawing, forming part thereof.

The drawing illustrates a plan view of

a portion of sheet metal showing my new design.

I claim:

The ornamental design for sheet metal as shown.

FRANK M. VOGAN.
